UNITED STATES PATENT OFFICE

2,442,800

RAIL FASTENER

Arnold E. Dentler, La Grange, Ill., assignor to
 W. H. Miner, Inc., Chicago, Ill., a corporation
 of Delaware

Application March 15, 1946, Serial No. 654,544

4 Claims. (Cl. 238—295)

1

This invention relates to improvements in rail fasteners, and more particularly to fasteners of the anchoring spike type.

One object of the invention is to provide a rail anchoring spike, which is self locking to effectively hold the same clamped against the flange of the usual rail.

A more specific object of the invention is to provide a fastener for rails in the form of a spike, driven into the tie which supports the rail, extending through the usual tie plate, having the head portion thereof provided with a laterally projecting arm at one side engaged over the flange of the rail to hold the rail in place, and a resilient locking finger at the opposite side having hooked shouldered engagement with the tie plate to lock the fastener against withdrawal from the tie.

Other objects of the invention will more clearly appear from the description and claims herein-after following.

In the drawing forming a part of this specification, Figure 1 is a transverse, vertical sectional view through a rail member and an associated tie plate and railroad tie, illustrating my improvements in connection therewith, said section being taken on the line 1—1 of Figure 2. Figure 2 is a top plan view of Figure 1, partly broken away. Figure 3 is a transverse, vertical sectional view through the rail member shown in Figure 1, said view being in a plane at one side of the tie, the tie and tie plate being shown in elevation and the spike member being shown as partly driven into the tie. Figure 4 is a view, similar to Figure 3, showing the spike member in another position. Figure 5 is a top plan view of the tie plate employed in connection with my improvements, said view being partly broken away.

In said drawing, 10 indicates the usual rail member and 11, the supporting tie. The rail 10 is of the type commonly employed, having laterally projecting base flanges 12—12, the upper surfaces of which are inclined upwardly toward the web 13 of said rail.

In carrying out my invention, I provide broadly a tie plate A, and an anchoring spike B which clamps against the rail flange and has shouldered engagement with the tie plate to lock the same to the plate.

The tie plate A is preferably of rectangular outline and is interposed between the base of the rail 10 and the tie member 11. As shown, the plate A is provided with an elongated, rectangular opening 14 adapted to accommodate the

shank of the spike B. The opening 14 is located to one side of the corresponding base flange 12 of the rail 10, as clearly shown in Figure 1, and has its length arranged at right angles to the length of the rail. The wall at the end of the opening 14, remote from the rail flange, is downwardly beveled, as indicated at 15, and a relatively heavy, upstanding lug 16, formed integral with said plate, is located adjacent said end of the opening and has a laterally projecting portion 17 which overhangs the opening. The portion 17 of the lug 16 presents a downwardly facing, flat abutment shoulder 18, which serves as a stop for locking the spike B in position. The end face of said projecting portion is beveled off to provide a cam face 19.

The spike B is made of spring steel material and heat treated to provide resiliency. It comprises a shank portion 20 and a driving head member 21. The shank portion is preferably of rectangular cross section and has its lower end pointed in the usual manner to facilitate driving the same into the tie. At one side thereof, the head member 21 is provided with a laterally extending, elongated arm 22 of the shape shown, engaging over the corresponding bottom flange 12 of the rail 10. As most clearly shown in Figure 1, the outer end portion of the arm 22 is downwardly thickened, as indicated at 23, said thickened portion presenting a rounded or convex underneath face which bears on the flange 12 of the rail. At the side of the spike B which is opposite the arm 22 of the head, the latter is provided with a depending locking spring finger 24, which is formed integral with said head. The locking finger is slightly offset with respect to the shank of the spike and is inclined away from said shank in downward direction, as shown in Figures 1 and 4. The lower end of the finger 24 is formed into a hook portion 25, which is adapted to lock beneath the projecting portion 17 of the lug 16. The end of the hook portion 25 is beveled off to provide a cam face 26 adapted to cooperate with the cam face 19 of the lug 16 of the tie plate. The top of the head 21 presents the usual flat driving face 27.

When the spike B has been driven home, as shown in Figure 1, with the arm 22 clamping the flange of the rail, the hook 25 of the finger 24 is engaged beneath the projection 17 of the lug 16 of the tie plate A, thus effectively locking the spike against upward movement.

In applying my improved rail fastener, the spike B is driven into the tie through the opening 14 of the plate A, as clearly shown in Fig-

ure 4. As the spike is driven further into the tie, the resilient finger 24 engages the lug 16 of the plate and rides over the same, being flexed toward the shank of the spike, as shown in Figure 3, by the cam face 26 thereof riding over the cam face 19 of the lug. When the spike is driven home, the hook portion 25 of the finger snaps beneath the projection 17 of the lug 16 to lock the spike against removal.

As will be evident, the spike B being made of spring steel, the arm 22 is sufficiently resilient to flex slightly in upward direction, thus easing the upward pull on the spike, due to upward pressure exerted on the clamping arm 22 by the rail flange, thereby preventing the spike from being loosened.

I claim:

1. In a fastener for a rail supported on a tie, the combination with a tie plate interposed between the rail and tie, said tie plate having a downwardly facing shoulder thereon; of a spike driven into the tie, said spike having a head portion overhanging a portion of the rail and clamping the same against the tie plate; and a resilient locking finger on said spike having a shoulder thereon engaged underneath the shoulder of the tie plate to lock said spike against upward movement with respect to the tie plate and against removal from the tie.

2. In a fastener for a rail supported on a tie, the combination with a tie plate interposed between the rail and tie, said plate having an opening therethrough and a downwardly facing shoulder thereon at said opening; of a spike having a shank and a head portion, said shank portion extending through the opening of said plate and being driven into the tie, said head portion having a laterally projecting arm at one side overhanging a portion of the rail to clamp the same against the tie; and a resilient locking finger depending from the head at the opposite side thereof, said finger having a shoulder in underlying engagement with the shoulder of the tie plate to restrain upward movement of said spike.

3. In a fastener for a rail supported on a tie, the combination with a tie plate interposed between the rail and tie, said plate having an opening therethrough; of a lug on said plate partly overhanging said opening; a spike having a shank and a head portion, said shank extending through the opening of the plate and into said tie; an arm laterally projecting from one side of said head and engaging over a portion of the rail to clamp the same on the tie; and a depending, resilient locking finger on the other side of said head, said finger having a hooked portion integral therewith and engaged beneath said overhanging portion of the lug of the plate to lock said spike against upward displacement with respect to said plate.

4. In a fastener for a rail having a base flange and supported on the usual tie, the combination with a tie plate interposed between said rail and tie, said tie plate having an elongated spike receiving opening therethrough adjacent one of the base flanges of said rail; of a lug overhanging said opening at the end thereof remote from said base flange of the rail; a spike having shank and head portions, said shank portion extending through the opening of the plate and into the tie; and an arm and a depending, resilient hooked finger extending from opposite sides of said head portion, said hooked finger engaging beneath said lug and said head bearing on said rail flange to clamp the same against the tie.

ARNOLD E. DENTLER.
